UNITED STATES PATENT OFFICE.

CHARLES CROMPTON, OF WORCESTER, MASSACHUSETTS.

STEAM-ENGINE.

SPECIFICATION forming part of Letters Patent No. 749,958, dated January 19, 1904.

Application filed March 3, 1900. Serial No. 7,171. (No model.)

To all whom it may concern:

Be it known that I, CHARLES CROMPTON, a citizen of the United States, residing at Worcester, in the county of Worcester and 5 Commonwealth of Massachusetts, have invented a new and useful Improvement in Steam-Engines, of which the following is a specification accompanied by drawings, forming a part of the same, in which—

- 10 Figure 1 represents a side elevation of an engine embodying my invention, with the steam-chest and cylinders shown in central sectional view. Fig. 2 is an end view of the engine represented in Fig. 1. Fig. 3 is an end view of a rotating valve-stem, showing the gearing by which it is rotated, with a hub of one of the gears shown in central sectional view. Fig. 4 represents a transverse sectional view of the steam-chest and rotating 15 valve on line 4 4, Fig. 1, showing the position of the rotating valve and its steam-ports for admitting steam to the cylinder 1 when its piston is in the position shown in Fig. 1. Fig. 5 represents the same transverse sectional view of the steam-chest and rotating valve as shown in Fig. 4, but with the steam-ports of cylinder 1 in their position when the rotating valve has been moved forward in order to reverse the engine. Fig. 6 is a trans- 20 verse sectional view of the steam-chest and rotating valve, with its exhaust-ports in position to exhaust the steam from cylinder 3 when its piston is in position shown in Fig. 1. Fig. 7 is a similar transverse sectional 25 view to that shown in Fig. 6, but with their exhaust-ports in their position when the rotating valve has been moved forward to reverse the engine. Fig. 7^a is a top view of a portion of the rotating valve, the upper half 30 having been removed, that portion of the valve being shown which extends from one end across the exhaust-ports of cylinders 1 and 2. Fig. 7^b is a detached view of the lever 56 and connected latch by which the engine is reversed. Figs. 8 to 21, inclusive, are 35 diagrammatic sketches which show the relative position of the steam-ports for each of the cylinders 1, 2, 3, and 4 when their pistons are in the position represented in Fig. 1, 40 Figs. 8, 12, 16, and 20 showing the position 45

of the admission-ports and Figs. 9, 13, 17, and 21 showing the position of the exhaust-ports; and Figs. 10 to 23, inclusive, are similar diagrammatic figures which show the position of the steam-ports for each of the four 55 cylinders when the rotating valve has been moved forward in order to reverse the engine.

Similar reference-figures refer to similar parts in the different views.

The object of my invention is to provide a 60 steam-engine adapted to be used as a motor for the propulsion of automobiles, yachts, and for such uses as require a prime mover in a compact form; and it consists in certain novel details of construction and arrangement 65 of parts, as hereinafter described, and set forth in the annexed claims.

The engine represented in the accompanying drawings as embodying my invention comprises four single-acting cylinders 70 provided with a common valve mechanism and having their pistons connected with a common crank-shaft.

Referring to the drawings, 1, 2, 3, and 4 denote the four cylinders of the engine, provided with pistons 5, 6, 7, and 8, connected by piston-rods 9, 10, 11, and 12 with a common crank-shaft 13 in the manner usual in engines of this class. One end of each of the cylinders is supported in a concentric socket 80 or circular recess 14 in one side of the rectangular steam-chest 15, and the opposite ends of the cylinders are supported by a plate 16, which is connected with the steam-chest 15 by means of screw-threaded tie-rods 17, and the 85 journal-boxes 18 of the crank-shaft are connected with a plate 16 by similar screw-threaded tie-rods 19. The ends of the cylinders are inserted in the concentric sockets 14 and are clamped between the steam-chest 15 and the plate 16 by means of the screw-threaded tie-rods 17. The steam-chest 15 is provided with a concentric hole to receive and form a bearing for a hollow cylindrical rotating valve 20. The hollow cylindrical rotating valve 90 20 is reduced at each end to form journals 21 and 22, the former rotating in a journal-bearing 23 and the latter rotating in a journal-bearing 24, by which the valve is held 95 from endwise movement. The bearing 24 100

consists of a stuffing-box provided with a follower 25 and an internally-screw-threaded cap 26, fitting an external thread on the stuffing-box, by which the follower is crowded against the packing 27. The steam-chest is provided with chambers 28, 29, and 30, which communicate with each other by steam-passages 31 in the corners of the steam-chest, as represented in Figs. 6 and 7. When the rotating cylindrical valve 20 is inserted in the steam-chest, it passes through the chambers 28, 29, and 30, forming steam-spaces between the inner walls of the steam-chest and the outside of the valve. Steam is admitted to the central steam-space 28 by a pipe 32 and from the steam-space 28 steam passes through the passages 31 to the steam-spaces 29 and 30. The journal 22 is solid, but the journal 21 is hollow and communicates with the interior of the cylindrical valve 20 and constitutes an exhaust-pipe through its open end. The rotating valve 20 is provided with openings 33, which communicate with the interior and periodically register as the valve rotates with exhaust-ports 34, leading from the cylinders, thereby permitting the exhaust-steam to pass into the center of the cylindrical valve 20 and be exhausted through the open end of the journal 22. The position of the opening in the valve relatively to the exhaust-port of the cylinder during the period of exhaust is represented in Fig. 6, which is a transverse sectional view of the steam chest and valve on the line 6-6, Fig. 1, showing the position of the valve relative to the exhaust-port of cylinder 3 when its piston is in the position shown in Fig. 1. The rotating valve 20 is also provided with a series of short cylindrical recesses 35, which as the valve rotates periodically connect the steam spaces 28, 29, and 30 with steam-admission ports which communicate with the cylinders 1, 2, and 3.

The arrangement of the steam-admission ports are the same in each of the four cylinders, and Fig. 4 represents a transverse sectional view of the steam chest and valve on line 4-4, Fig. 1, showing the steam-admission ports 36 and 36^a of cylinder 1 and the position of the valve and its recesses 35 when the piston of the cylinder is in the position shown in Fig. 1. The steam-chest bears against the rotating valve at 37 and 38 upon each side of the ports 36 and 36^a, so as to cut off the communication between the steam-spaces and the admission-ports, except as communication is established between them through the cylindrical recesses 35 in the valve. The bearings 37 are slightly greater than the width of the recesses 35, and the bearings 38 are narrower than the width of the recesses 35, as shown in Fig. 6, so that whenever the recesses 35 span the narrow bearings 38 as the valve rotates communication is established between the steam-space and the admission-ports, thereby admitting steam to the cylinders. The ad-

mission-port 36 is connected by a recess 35 in the valve directly with the steam-space 29, and the steam-chest is provided with a recess 39 beneath the valve 20, which communicates at one end with the steam-space 29 to provide a passage for steam through the admission-port 36^a. The recesses 35 and the exhaust-openings 33 are arranged on the rotating valve 20 to admit exhaust-steam at regular intervals successively to each of the cylinders 1, 2, 3, and 4 by a continuous rotary movement of the valve as it is driven from the crank-shaft 13 by means of connecting mechanism, consisting of an intermediate shaft 40, journaled in bearings 41 42 and carrying a bevel-gear 43 at one end, which engages a pinion 44 on the crank-shaft 13 and having a pinion 45 at the opposite end which engages a bevel-gear 46, attached to the journal 22 of the valve 20, by which a rotary movement is given to the valve in the same direction as the rotation of the crank-shaft 13. The pinion 45 is provided with a hollow hub 47, which incloses a collar 48, attached to the shaft 40, which serves with the journal-bearing 42 to hold the pinion 45 from longitudinal movement. Inclosed within the hollow hub 47 of the pinion 45 is a sleeve 49, which is capable of sliding on the shaft 40 and having a spline connection therewith by means of splines 50. The sleeve 49 carries on diametrically opposite sides short studs 51, provided with rolls 52, which are inclosed in spiral-shaped slots 53 in the hub of the pinion 45, by which a rotary motion of the shaft 40 is communicated to the pinion. The sleeve 49 is provided with a neck 54 to receive a fork 55, pivotally connected with a lever 56, which is pivoted to a bracket 57 and is provided with a latch 58, adapted to engage notches 59 in a bracket attached to the framework and bent in the arc of a circle concentric with a pivot of the lever 56. The latch 58 is thrown into engagement with the notches 59 by a spring 61 acting against a pivoted lever 62, by which the latch is withdrawn from the notches in the usual manner in devices of this class. In Fig. 1 of the drawings the sleeve 49 is shown in its highest position, holding the driving-studs 51 at the upper ends of the spiral slots 53. The depression of the handle 56 will move the sleeve down and carry the studs 51 to the lower end of the spiral slots 53, causing the pinion 45 to be turned forward a short distance or in the direction of its movement when the engine is running, thereby slightly turning the valve 20 forward and changing the position of its openings 33 and recesses 35 relatively to the steam admission and exhaust ports. The advanced movement of the valve 20, caused by the downwardly-sliding movement of the sleeve 49, will move the recesses 35, by which steam is admitted to the cylinder No. 1 when in the position shown in Fig. 4, to the position shown in Fig. 5, and the exhaust-port of the valve, 130

by which steam is exhausted from cylinder 3 when in the position shown in Fig. 6, will be moved to the position shown in Fig. 7, thereby closing the steam-admission ports of cylinder No. 1 and the steam-exhaust ports of cylinder 3, which had before been open.

Referring to the diagrammatic drawings Figs. 8 to 23, inclusive, Fig. 20 represents the position of the rotating valve 20 with reference to the steam-admission ports of cylinder No. 1 when its piston is in the position shown in Fig. 1, with the rotating cylinder moving in the direction of the arrow *a*, with steam passing through the ports in the direction indicated by the arrows *bb*. Fig. 21 represents the position of the rotating valve with reference to the exhaust-ports of cylinder No. 1. Figs. 16 and 17 show the relative position of the rotating valve to the admission and exhaust ports of cylinder 2; Figs. 12 and 13, the position of the valve with reference to the admission and exhaust ports of cylinder 3, and Figs. 8 and 9 the position of the valve to the admission and exhaust ports of cylinder 4, the arrows upon these figures showing, like those in Fig. 20, the direction of the rotary movement of the valve and the movement of the steam through the ports. The recesses 35 are preferably slightly shorter than the admission-ports, and steam is admitted from the steam-spaces of the steam-chest through the recesses 35 to the admission-ports by a movement transversely to the axis of the valve and not in a direction parallel with the axis of the valve—that is, the movement of steam as the valve begins to open is through a narrow crack between the edge of the steam-chest bearing and the edge of the recess, which is not the case in rotating valves provided with annular steam-spaces formed in the rotating valve itself. In that class of valves the movement of steam is from the annular steam-space lengthwise the recess. If it is desired to reverse the engine, the valve is moved preferably slightly forward by the depression of the lever 56, changing the position of the recesses on the rotating valve from those shown in Figs. 8, 12, 16, and 20 to their position shown in Figs. 10, 14, 18, and 22, so that steam will be admitted into cylinders 3 and 4 and exhausted from cylinders 1 and 2, which will reverse the engine, cause the crank-shaft and connected rotating valve to turn in the opposite direction, as indicated by the arrows *c*. When the engine is to be again run in a forward direction, the lever 56 is raised, thereby sliding the studs 51 upwardly in the spiral slots 53 and slightly rotating the valve 20 by the independent movement of the pinion 45 relatively to the rotating shaft 40.

The framework in which the operative parts of the engine are contained, comprising the steam-chest 15, plate 16, journal-boxes 18, and connecting tie-rods 17 and 19, can be supported by connecting the steam-chest 15 and

plate 16 in any desired manner with a supporting-stand or with an inclosing framework, (not shown in the drawings,) according to the use to which the engine is put, and the engine can be placed in any desired position with the cylinders in a horizontal, vertical, or oblique position. I have shown four cylinders; but I do not confine myself to any specific number of cylinders or valves. Neither do I wish to confine myself to the specific method shown of driving the rotating valve or to the specific position of the valve relatively to the cylinders.

What I claim as my invention, and desire to secure by Letters Patent, is—

1. In an engine, the combination of a hollow bar forming a steam-chest and having a series of sockets to receive the cylinders, a series of cylinders held in said sockets, said bar having a series of steam-spaces communicating with said cylinders and a valve contained in said hollow bar, whereby the flow of steam to said cylinders is controlled, substantially as described.

2. In an engine, the combination of a hollow bar forming a steam-chest and having sockets to receive the ends of the cylinders, cylinders held in said sockets, a plate bearing against the opposite ends of said cylinders, tie-rods by which the cylinders are clamped between said hollow bar and said plate, and a valve contained in said hollow bar to control the flow of steam to said cylinders, substantially as described.

3. In an engine, the combination of a hollow bar forming a steam-chest and having sockets to receive the ends of the cylinders, cylinders held in said sockets, a plate bearing against the opposite ends of said cylinders, tie-rods between said plate and said hollow bar, journals for a crank-shaft and tie-rods connecting said plate and said journals and a valve for controlling the distribution of steam from said hollow bar to said cylinders, substantially as described.

4. In an engine, a steam-chest having admission-ports leading to the cylinders, a cylindrical rotating valve journaled in said steam-chest and having a series of recesses in its periphery shorter than said admission-ports, a bearing-surface on the steam-chest at the side of the admission-ports bearing against said cylindrical valve, said bearing-surface being of less width than the width of said recess, substantially as described.

5. In an engine, the combination of a steam-chest having a longitudinal, cylindrical opening to receive a rotating cylinder journaled therein and having recesses in its periphery, annular chambers in said steam-chest around said cylinder and forming steam-spaces, a passage in said steam-chest leading to a source of steam-supply, admission-ports leading from said annular steam-spaces to the cylinders, the recesses in said rotating cylinder being shorter than said admission-ports and arranged to

periodically connect said steam-spaces and said ports and means for continuously rotating said cylinder, substantially as described.

6. In a steam-engine, the combination of a steam-chest, a rotating valve journaled in said steam-chest, steam-admission ports leading to a steam-cylinder, a steam-space around said valve, recesses in the periphery of said valve, said steam-chest having a bearing-surface against said valve on one side of the steam-ports, greater than the width of said recesses and having a bearing-surface against said valve on the opposite side of said ports, less than the width of said recesses, whereby said recesses are caused to periodically span said narrow bearing-surfaces and thereby connect the steam-space with said ports, substantially as described.

7. In an engine, the combination with a series of single-acting cylinders, of a common steam-chest extending across the ends of said cylinders and provided with a longitudinal, cylindrical opening for a rotating cylindrical

valve with recesses in the sides of said opening, a cylindrical valve journaled in said steam-chest and closing said recesses to form annular steam-spaces around said valve, a passage in said steam-chest connecting said annular steam-spaces with a source of steam-supply, admission-ports leading from said annular steam-spaces to said cylinders, recesses in the periphery of said valve by which the flow of steam to said cylinders is controlled, a longitudinal exhaust-passage through said valve, exhaust-ports in said steam-chest and openings in said valve by which said exhaust-ports and said exhaust-passage are periodically connected, substantially as described.

In testimony whereof I have signed my name to this specification, in the presence of two subscribing witnesses, this 1st day of March, 1900.

CHARLES CROMPTON.
